UNITED STATES PATENT OFFICE.

EMIL R. DRAVER, OF RICHMOND, INDIANA, ASSIGNOR OF ONE-HALF TO ORRIN DRAVER, OF RICHMOND, INDIANA.

FRICTIONAL WINDOW-SASH HOLDER.

Application filed September 19, 1924. Serial No. 738,596.

My present invention provides an extremely simple and highly efficient frictional window sash holder or support adapted to be used in lieu of counterweights and the like to hold the window sash in any and all desired vertical adjustments, and, generally stated, the invention consists of the novel devices, combinations of devices and arrangements of parts hereinafter described and defined in the claims.

For the application of window counterweights to sashes, the window frames must be designed with weight boxes and provided with cord pulleys, and when the cords and weights are applied, the weights, if dropped, can be replaced only with considerable difficulty and, moreover, if weights of under-weight or over-weight are used, as frequently happens, then the window sash will not be properly counterbalanced and are liable to be moved accidentally or by the defect in the counterweighted action.

My invention provides a frictional sash holder that will obviate the defects of window weights and reduce the cost of installation, and which, moreover, may be readily applied to window frames of the simplest form made without weight boxes or spaces.

The invention, in several of its commercially practicable forms, is illustrated in the accompanying drawings, wherein like characters indicate like parts throughout the several views.

Referring to the drawings:

Fig. 1 is an elevation illustrating my invention applied to the upper and lower sashes of a window, portions of the frame being broken away and the said parts being viewed from the inner side of the room;

Fig. 2 is a vertical section taken approximately on the line 2—2 of Fig. 1, showing the parts on a larger scale than in Fig. 1 and some parts being broken away;

Fig. 3 is a fragmentary view in elevation showing a portion of the upper sash, some parts being sectioned on the line 3—3 of Fig. 2;

Fig. 4 is an edge elevation of the parts shown in Fig. 3, looking at the same from the left toward the right in respect to Fig. 3;

Fig. 5 is a horizontal section taken on the line 5—5 of Fig. 3;

Fig. 6 is an end elevation of one of the anchoring sleeves, preferably used as a part of the improved device;

Fig. 7 is a section on the line 7—7 of Fig. 6;

Fig. 8 is a perspective showing in detail one of the spring-anchoring clips;

Fig. 9 is a fragmentary view partly in elevation and partly in vertical section, illustrating a modified form of the frictional sash support;

Fig. 10 is a perspective showing in detail the spring-anchoring clip of the arrangement shown in Fig. 9;

Fig. 11 is a view corresponding to Fig. 9, but illustrating a still further modified form of the spring-anchoring clip; and

Fig. 12 is a perspective showing in detail the anchoring clip illustrated in Fig. 11.

The window frame structure, which may be of the very simple form indicated, is indicated as an entirety by the numeral 13 and the wall of a building to which it is applied is indicated by the numeral 14. This window frame, on its opposite sides, is provided with the customary outer stop strips 15, intermediate stop strips 16, and inner stop strips 17. The upper sash 18, as is usual, is arranged to slide in channels formed between the stop strips 15 and 16, and the lower sash 19 is arranged to slide in the channels formed between the stop strips 16 and 17. The stop strips 16 and 17 are removably held in one position, preferably in the usual way, said strips being set into grooves formed in the sides of the window frame and said stop strips 17 being secured to the sides of the window frame by the customary blades, not illustrated.

The invention applied as illustrated in Figs. 1 to 8, inclusive, will first be described:

The window sashes 18 and 19, in their opposite vertical edges, are formed with grooves 18^a and 19^a, respectively, to form clearance passages for tension rods presently to be described. The grooves 19^a in the lower sash 19 preferably run from top to bottom thereof, while the grooves 18^a in the upper sash 18 preferably terminate short of the bottoms thereof so as to prevent said slots from leaking air at the exposed lower portion of the outer sash. In the lower sash, the grooves are not exposed at their ends at the exterior of the window or to the outside atmosphere.

To support the sashes with equal friction or tension at opposite sides, a pair of laterally spaced friction or tension devices is applied to each sash, although, for a less

efficient job, each sash might be supported by one tension device. In what is at present believed to be the preferred form of the tension device illustrated in Figs. 1 to 8, inclusive, each such tension device comprises a rod 20, a spring-anchoring clip 21, a tension spring 22, and a clip-anchoring sleeve 23, all of which are arranged to work in the respective grooves 18^a or 19^a, as the case may be. Also in this preferred arrangement, the four tension rods, of which there are two for each sash, are rigidly attached at their upper ends by threaded engagement or otherwise to heads 24, which, by suitable devices such as wood screws 25, are pivotally attached to the upper side portions of the window frame 13. These heads 24 are of such width that, when the sashes are raised to extreme positions, they will pass freely into the upper extremities of the respective grooves 18^a or 19^a, as the case may be. These tension rods 20 are, therefore, freely suspended from their upper ends so that they may swing laterally, as will hereinafter appear, and may oscillate slightly so that they are self-adjusting to the movements of the sashes and the cooperating spring-anchoring clips.

The tension springs here illustrated are closely coiled springs that are normally distorted or bent transversely, so that they tend to assume a humped or crooked formation and so that, when telescoped onto the cooperating tension rods, they will engage the same with sufficient friction to hold the respective sashes in any vertical position in which they may be adjusted. To cause these tension springs to move with the sash, the spring-anchoring clips 21 are employed and these clips, as here illustrated, are each formed from a single piece of stiff wire bent to form laterally offset axially aligned eyes or loops 21^a and a laterally projecting trunnion or finger portion 21^b, which latter projects at a right angle to the axis of said eyes 21^a. The clip-anchoring sleeves 23^a are preferably tapered and externally threaded and are slit at their outer ends so that a screw driver may be applied thereto to screw the same into seats formed in the sashes at the bottoms of the grooves thereof.

The tension springs 22 are placed between the eyes 21^a of the respective anchoring clips and the rods 20 are passed through said eyes and the cooperating springs. In applying the tension devices to the sashes, assembled as just indicated, the anchoring sleeves 23 having first been screwed into the sashes, the trunnions 21^b are inserted into the respective anchoring sleeves 23, as best shown in Figs. 3, 4 and 5, and then the upper ends of the rods will be attached to the window frame by application of the wood screws 25 to the heads 24.

When the stop strips 17 and 18 are re-

moved, the sashes and their cooperating tension rods may be swung inwardly, as indicated in one instance in Fig. 2, and when thus swung inwardly, the sashes may be slid onto or off from the said rods without requiring detachment of the rods from the window frame. From this, it follows, of course, that, if desired, in first assembling the sashes and tension devices on the window frame, the tension rods may be pivotally attached to the frame, and the tension devices 21 and 22 attached to the sashes, and the said elements 21 and 22 then slid onto the rods 20.

Not only are the tension rods 20 free for the above described lateral oscillatory movements, but they are free for slight oscillatory movements in the plane of the sashes, so that said rods thus suspended from their upper ends and free at their lower ends are self-adjusting to any irregularities in the movements of the sashes or to any inaccuracies in the construction and manner of assembling. The feature of suspending the rods from one end only, and preferably only from their upper ends, is important because it permits the sashes, when the stop strips are removed, to be swung into the room or out of working positions without first detaching the sashes from the tension rods. This feature is important for several reasons. In the first place, it makes it possible to quickly remove the sashes and replace the same, and in the second place, it makes it possible to swing the sashes into the room or out of position so that they may be readily cleaned on both sides, even while still applied to the respective tension rods. The so-called tension rods, in these operations, serve as suspending rods for holding the sashes even when out of working positions.

The construction illustrated in Figs. 9 and 19 is very much like that already described in detail in connection with Figs. 1 to 8, inclusive, but a somewhat modified form of spring-anchoring clip is employed. The spring-anchoring clips 26 here provided are each made from a single piece of wire bent to form laterally offset axially aligned eyes 26^a and an anchoring eye 26^b, which latter is the lower end of the clip and is anchored to the sash preferably by a screw 27. The distorted springs 22 are placed between the aligned eyes 26^a and the rods 20 are passed therethrough, as in the construction previously described. In this construction and in the construction previously described, the spring-anchoring clips are pivotally anchored to the sashes so that they also are self-adjusting. The numeral 18^a indicates stop strips applied to the frame 13 below the sash 18 to prevent the latter from being slid downward off from the tension rods 20.

The construction illustrated in Figs. 11 and 12 is also the same as before described,

except that a still further modified form of 5 spring-anchoring clip is employed. A spring-anchoring clip of this construction is either a casting or other form of metal channel secured by a screw 29 or the like to the sash at the bottom of the edge groove thereof and provided with outstanding lugs 29 between which the distorted spring 22 is applied. To pass the cooperating tension 10 rod 20 through the spring 22 and through the lugs 29, the latter are either perforated or notched, but as illustrated, said lugs are provided with notches 30 that embrace the rod 20.

15 From what has been said, it will be understood that the invention described is capable of various modifications, all within the spirit of the invention herein disclosed. The distorted or transversely offset coiled spring, 20 while an extremely simple device of small cost, is, at the same time, the most efficient kind of friction device for engagement with the tension rod.

The importance of anchoring the tension rods with freedom for lateral swinging or shifting movements to adapt themselves to the movements of the sashes, will be appreciated when it is considered that rigidly supported tension rods would not adapt themselves to movements of the sashes but would tend to be the controlling guides for the sashes and there would, therefore, tend to be a conflict between the guiding functions of the rods and of the sash-guiding channels. 35 My described arrangement of the said elements affords a structure that does not need to be applied with any great care or close attention to afford a completely operative and satisfactory arrangement for the purposes had in view. The various features noted 40 and those that are obvious make this simple arrangement a highly satisfactory, low cost device for the purposes had in view.

What I claim is:

45 1. The combination with a sliding sash, of a tension rod anchored against endwise movements but free for lateral shifting movements and extended along the line of travel of the sash, and a friction device applied to the sash and slidably engageable with said tension rod.

50 2. The combination with a window frame and a sash slidable therein, said sash having a grooved vertical edge, of a friction device applied to said sash in the groove thereof, and a tension rod pivotally anchored to said frame at one end and working frictionally through the friction device of said sash.

55 3. The combination with a window frame and sash, of a tension rod anchored to said

frame, a threaded clip-anchoring sleeve applied to said sash, a spring-anchoring clip 65 slideable on said tension rod and having a laterally projecting trunnion seated in said anchoring sleeve, and a spring seated in said clip for travelling movements therewith and having frictional engagement with said tension rod.

4. The structure defined in claim 3 in which said spring-anchoring clip is made 70 from a single piece of wire bent to form the laterally projecting trunnion thereof and to form axially aligned eyes through which said tension rod is passed.

5. The combination with a window frame 75 and sash slideable therein, of laterally spaced tension rods pivotally connected to said frame at one end and extended along the line of travel of said sash, said sash having friction devices applied thereto and frictionally slideable on said tension rods, the 80 said frame having removable stop strips which when removed permit the sash and tension rods to be swung laterally from working positions.

6. The combination with a window frame and sash slideable therewith, of a tension rod pivotally connected to said frame at its upper end and extended vertically along the line of travel of the sash, said sash having 90 a frictional device slideable on said tension rod, the said rod being capable of oscillatory movements to move the sash laterally from working position.

7. The combination with a window frame 95 and sash slideable therein, of a tension rod anchored to said frame, a spring-anchoring clip pivotally connected to said sash and a transversely distorted coiled spring anchored to said sash by said clip and frictionally engageable with and slideable on said rod, and which clip is formed with perforated vertically spaced lateral projections through which said rod is passed and is provided 100 with a laterally projecting trunnion pivotally seated in said sash.

8. The combination with a window frame and sash slideable therein, of a tension rod anchored to said frame, a spring-anchoring clip pivotally connected to said sash and a transversely distorted coiled spring anchored 110 to said sash by said clip and frictionally engageable with and slideable on said rod, and which clip is formed from a single piece of wire bent to form laterally offset eyes 115 through which said rod is passed and is provided with a laterally projecting trunnion pivotally seated in said sash.

In testimony whereof I affix my signature
EMIL R. DRAVER
